(57) **CLAIM**

The ornamental design for a cleaning cabinet, as shown and described.

DESCRIPTION

FIG. 1 is a perspective view of a cleaning cabinet, showing my new design;

FIG. 2 is another perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof;

FIG. 7 is a bottom plan view thereof;

FIG. 8 is a partial enlarged view of FIG. 1;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 2;

FIG. 13 is a partial enlarged view of FIG. 2;

FIG. 14 is a partial enlarged view of FIG. 3; and,

FIG. 15 is a partial enlarged view of FIG. 7.

The short dash broken lines in the figures depict portions of the cleaning cabinet that form no part of the claimed design. The long dash broken lines in the figures depict boundaries of enlarged portions and form no part of the claimed design.

1 Claim, 14 Drawing Sheets
